UNITED STATES PATENT OFFICE.

SOLOMON W. WIBEL, NATHAN J. McALONEY, AND WILLIAM R. CUNNINGHAM, OF DENVER,
COLORADO.

ELECTRIC LOCK.

No. 888,285.

Specification of Letters Patent.

Patented May 19, 1908.

Application filed January 29, 1906. Serial No. 298,424.

To all whom it may concern:

Be it known that we, SOLOMON W. WIBEL, NATHAN J. McALONEY, and WILLIAM R. CUNNINGHAM, all citizens of the United States, residing at the city and county of Denver and State of Colorado, have invented certain new and useful Improvements in Electric Locks; and we do declare the following to be a full, clear, and exact description 10 of the invention, such as will enable others skilled in the art to which it appertains to make and use the same, reference being had to the accompanying drawings, and to the letters and figures of reference marked thereon, which form a part of this specification.

Our invention relates to electric lock mechanism or more correctly speaking to a lock in which the latch or movable locking device or bolt is moved to the unlocked position 20 through the instrumentality of an electro magnet of any suitable type. Provision is made whereby a special device is required in order to close the circuit in which the controlling electro-magnet is located. A switch 25 for controlling the circuit may be located at any suitable distance from the place where the door to be unlocked is located.

Our improved mechanism will be described herein with special reference to its use as a 30 lock for car doors, though it must be understood that it may be employed to advantage in many other relations where a safety lock is required.

In the use of our mechanism in connection 35 with car doors, it is evident that the means employed may be considerably varied. The circuit wires may be extended for any desired distance along the track and suitably supported. The car when run anywhere in 40 the vicinity of these wires may be unlocked by the use of a suitable rod or pole having electric conductors running through it and protruding from the top thereof whereby they are adapted to be hooked over the circuit wires. At the opposite extremity of the pole, a key may be connected with these conductors, the same having contacts adapted 45 to bridge the space between electrodes carried by the lock casing, whereby the circuit is closed through the electro-magnet which acts to move the latch or bolt thus releasing the door. It is evident that other means 50 may be employed between the external circuit and the magnet circuit for transmitting 55 the current to the latter.

Having briefly outlined our improved electric lock mechanism, we will proceed to describe the same in detail reference being made to the accompanying drawing in which is illustrated an embodiment thereof.

In this drawing, Figure 1 is a side elevation of a car equipped with an electric lock and shown in connection with means for transmitting the current from the circuit wires or external circuit, to the wires of the magnet or internal circuit. Fig. 2 is a fragmentary view of a car showing the lock casing in section, and the lock mechanism in elevation. This view may be said to be a section taken on the line 2—2 Fig. 3. Fig. 3 is a section 70 taken on the line 3—3 Fig. 2 looking downwardly. Fig. 4 is a view similar to Fig. 2 but entirely in elevation. Fig. 5 is a perspective view of the key or device for bridging the electrodes with which the wires of the 75 magnet circuit are connected.

The same reference characters indicate the same parts in all the views.

Let the numeral 5 designate the body of a car provided with a sliding door 6 having a 80 keeper 7 which protrudes into a recess 8 formed in the casing 9 surrounding the door of the car. Mounted on the car adjacent the recess 8, is a casing 10 in which is located an electro-magnet 12.

As shown in the drawing the locking device proper is of lever-like structure being composed of a bar 12^A fulcrumed at 14 on an upright part 13. The forward extremity of this bar is hook-shaped as shown at 15 whereby it is adapted to engage or coöperate with the keeper 7 for locking the door. The extremity of the bar 12^A opposite its locking 90 extremity, consists of a member 16 extending at a suitable angle to the bar 12^A. The 95 free extremity of this member 16 is provided with an armature plate 17 located in suitable proximity to one extremity of the magnet 12. When this magnet is deenergized, the locking bar occupies the position shown in full lines 100 in Fig. 2. When, however, the magnet is energized the electro-magnetic force acting on the armature plate 17, throws the locking device to the dotted line position (see Fig. 2), whereby the keeper 7 of the sliding door is released, allowing the door to be opened at 105 pleasure.

The lock casing 10 is provided with two separated electrodes 19 which are insulated from each other. These electrodes are 110

connected with the magnet coils by conductors 21 and 22. The coils of the magnet are normally deenergized or inactive.

In Fig. 1 of the drawing a circuit is diagrammatically illustrated comprising an electric source A, conductors B and C leading from the opposite extremities of the source. A switch E is so located that it can only be operated by an authorized person. Assuming that the conductors B and C extend along the track upon which the car 5 is run, a person who desires to open the car door 6, must first make arrangements to have the switch E of the circuit closed. He then takes a pole D through which run conductors F and G having hook-shaped extremities at one end of the pole adapted to engage the wires B and C. As these conductors run through the pole, they are exposed at the lower end thereof and terminate in contacts H and I mounted on a block J having a hand piece K. These contacts H and I are located just far enough apart to bridge the space between the electrodes 19 mounted on the lock casing. The conductors F and G form a flexible connection between the block J and the pole, thus permitting convenient manipulation of the block for the purpose of closing the magnet circuit. It must be understood that other means may be employed for transmitting the current from the external or main circuit to the wires of the magnet circuit.

From the foregoing description the use and operation of our improved mechanism will be readily understood. Assuming that the car door is locked and that it is desired to open the lock, an authorized person first ascertains that the switch E is closed whereby the current from the source passes through the conductors B and C. Then by the use of the pole D he hooks the conductors F and G over the wires of the main circuit, and applies the contacts H and I to the electrodes 19 of the lock casing thus closing the magnet circuit. The magnet being energized acts upon the armature plate 17 to throw the latch to the dotted line position in Fig. 2, permitting the door of the car to be opened. It is preferred to employ a spring of suitable construction which acts normally to hold the locking device in the locked position. In Fig. 2 of the drawing a leaf spring 20 is illustrated. It will be understood that if the locking device occupies a

vertical position as assumed in the drawing, the device 12^A will assume the locking position by gravity. However, if the locking latch were in a horizontal position which might be the case, a spring will be required to throw it normally to the locked position.

In applying our improved lock mechanism to a car or other structure, the lock casing 10 is connected with the wall of the car by means of bolts 23 whose head extremities are concealed within the casing and whose threaded extremities to which the nuts are applied, are located on the inside of the car.

The recess 8 into which the keeper 7 protrudes as well as the hooked extremity of the locking device, is closed exteriorly by a plate 24 with which bolts 25 are formed integral. These bolts pass through the wall of the car surrounding the door, and are secured by nuts on the inside. The keeper is also secured by bolts 26 whose head extremities only are exposed, their threaded extremities being located on the inside of the car and suitably secured by nuts. By virtue of this construction an evilly disposed person has no opportunity to tamper with the mechanism or open the car door, without first closing the magnet circuit and energizing the magnet as heretofore explained.

Having thus described our invention, what we claim is:

The combination with a keeper connected with the part to be secured, a locking device suitably fulcrumed above the electro-magnet, the locking device having an armature part adapted to be acted on by the energized magnet to operate the locking device, stationary terminals suitably separated and electrically connected with the coils of the magnet, an external circuit, and a portable device adapted to be connected with the external circuit at one extremity and with the terminals of the magnet at the other extremity, to complete the circuit through the magnet coils.

In testimony whereof we affix our signatures in presence of two witnesses.

SOLOMON W. WIBEL.

NATHAN J. McALONEY.

WILLIAM R. CUNNINGHAM.
